ELECTRIC CABLE SYSTEM

Charles E. Bennett, Ridgewood, N. J., assignor
to The Okonite-Callender Cable Company, In-
corporated, Paterson, N. J., a corporation of
New Jersey

Application September 13, 1941, Serial No. 410,654

3 Claims. (Cl. 174--25)

This invention relates to improvements in electric cable systems and is particularly directed to high tension cable systems wherein insulated conductors are loosely enclosed in a pipe line which is filled with an insulating fluid under pressure.

In one well known cable system such as disclosed, for example, in my prior Patent No. 2,015,063 the conductors are insulated with oil pervious, oil impregnated paper and enclosed in a steel pipe line which is kept filled with oil or other insulating fluid under pressure.

Certain difficulties and inconveniences have been experienced in manufacturing, shipping and installing this prior system. For example, in shipping, because of the fact that the cable is insulated with oil pervious, oil impregnated paper, it has been necessary to either ship the cable in a sealed drum or to sheath the cable with a temporary lead sheath in order to protect the cable against contamination with water or other deleterious materials and to prevent loss of the insulating oil. If the cable is shipped in a temporary lead sheath it is necessary to remove the sheath in the field as the cable is being drawn into the pipe line and should the sheath be removed in damp weather there is danger of moisture being absorbed by the cable, and it is exceedingly difficult to remove this moisture. The method generally employed for removing this moisture from the system involves considerable installation disadvantages; for instance, in the case of a long line oil is pumped through the line into a tank, and then the oil is treated to remove the moisture picked up. This is done over and over again until the oil comes through free of moisture.

Other objections to shipping in a temporary sheath are (1) the space required at the site of installation by the construction force to strip off the lead sheath as the cables are being drawn into the pipe line and the necessity in inclement weather for housing to protect the cable; (2) the weight of the lead itself. In many instances this is half the weight of the cable. This adds to the cost of shipment to the job, to which must be added the cost of return of the scrap lead to the factory.

Where these cables are shipped in oil containers instead of in a lead sheath, considerable money must be spent for duplicate reels of a special design which are costly. Then again these reels are very heavy when filled with oil which increase the shipping costs.

The present invention presents an improvement over the prior cable system mentioned above and overcomes the disadvantages outlined.

Broadly the present invention provides for insulating the cable with fluid impervious material and shipping the cable dry to the installation site. This eliminates the necessity of shipping in a temporary lead sheath or special reels and automatically eliminates the disadvantages above referred to inherent in such systems.

The insulating material I employ may be the usual paper tape employed for insulating high tension paper insulated power cables but under the present invention this tape is treated with wax or other suitable material to render the same impervious to oil, water and like fluids.

After the cable has been insulated with this fluid impervious insulation it is wrapped with the usual metal shielding tape and then covered with a moistureproof covering. This covering is readily applied by dipping or drawing the cable through a paraffin bath, for example.

It will be appreciated that up to this point the cable has not been evacuated nor has it been filled with oil or any other insulating fluid.

The cable is shipped in this condition to the installation site, and after the pipe line has been dried out the cable is drawn in.

By reason of the fact that the covering of the cable is moistureproof the cable can be drawn in without danger of contamination with moisture, and any moisture collecting on the covering can be wiped off without difficulty. After the cable is drawn in the same is evacuated and dried out thoroughly by electrically heating the conductor, after which the insulating fluid, such as degassed oil, is introduced and placed under a substantial pressure, for example, seventy-five pounds per square inch minimum.

In the accompanying drawing I have illustrated a cable system made and installed in accordance with my invention.

In the drawing:

Fig. 1 is a sectional view of my improved cable; and

Fig. 2 is an enlarged elevational view of one of the insulated conductors.

Referring to the drawing in detail: 2 designates the conductor. This conductor is of usual construction, say of the standard stranded type. About this conductor I apply the insulating material 4. This material is preferably paper tape treated with wax to make it fluid impervious.

It must have a low power factor around .5% at room temperature, a relatively low power factor as compared with a power factor of 5% which is that of varnished cambric and which unfits the cable for my purpose which is high tension power

transmission. The wax or other material employed to render the cable fluid impervious must be capable of withstanding temperatures in excess of 90° C. which is about the maximum temperature encountered in cable practice.

6 designates the usual shielding tape applied about the fluid impervious insulation, while 3 designates D-shaped protective armor applied about the cable exterior to protect the cable against injury when being pulled into the pipe line, and to reduce the friction between the cable and pipe line, thus facilitating drawing in. After the cable is made up it is treated with paraffin or some other moistureproof material, by drawing the cable through a suitable bath of the moistureproofing material, or in other convenient fashion. This moistureproofing material is only a temporary coating to protect the cable against the entry of moisture during handling, shipping and installing, and for this reason has a melting point below 90° C., which, as above pointed out, is maximum temperature usually met with in cable operation, so that after the cable is installed the paraffin will be melted and will no longer prevent the passage of insulating fluid to between the layers composing the insulating wall 4.

The cable or cables is or are drawn into the pipe line 10 which is of steel or other suitable material which is capable of withstanding high internal pressures of the order of several hundred pounds per square inch, the pipe having first been thoroughly dried.

The cable is next heated electrically, by suitably connecting the conductor to a source of power, thoroughly to evacuate and dry the cable. As previously pointed out, the wax or other material with which the cable insulation is pretreated to render it fluid impervious has a high melting point, in excess of 90° C., and in this connection I wish to note its melting point must be above that reached by the cable in the evacuating and drying stage just referred to.

Finally the pipe line is filled with oil or other insulating fluid which is placed under pressure, preferably not less than seventy-five pounds per square inch.

By placing the oil under pressure it will be apparent that while no oil can pass into the insulating paper because the same is fluid impervious, the oil will be forced into and fill all of the spaces between the laminations of the fluid impervious insulation.

It will be apparent that the pressure will promote connection between adjacent paper layers.

In addition to the several advantageous fea-

tures above referred to, it will be apparent to those skilled in this art that the total volume of oil or other fluid insulation employed is very much reduced in volume as compared with prior structures employing fluid pervious material, and as a consequence the expansion difficulties inherent in the usual cable which employs all pervious paper and oil are eliminated.

I have illustrated my invention as applied to 10 multi-conductor cable systems. It will be understood, of course, that the same is applicable equally well to single conductor cable systems.

What I claim is:

1. An electric cable comprising in combination a conductor, paper tape treated with a material rendering the tape fluid-impervious and having a higher melting point than the maximum operating temperature of the cable wrapped spirally layer upon layer about the said conductor 20 to build up an electrically insulating wall about the conductor, a coating of moistureproof material about said insulating wall, said moistureproof material having a melting point lower than the maximum operating temperature of the cable, a 25 body of insulating fluid under superatmospheric pressure surrounding the insulated conductor, an enclosure for the insulating fluid and the insulating conductor, loading of the cable disintegrating the said moistureproof material and permitting 30 access of the insulating fluid between the layers of paper composing said insulating wall.

2. An electric cable comprising a conductor insulated with laminated paper treated with a material rendering the paper fluid-impervious and 35 having a higher melting point than the maximum operating temperature of the cable, the insulated conductor having a coating of a moistureproof material which has a melting point lower than the maximum operating temperature of the 40 cable, a body of insulating liquid under pressure surrounding the insulated conductor, an enclosure for the insulating liquid and the insulated conductor, loading of the cable disintegrating the moistureproof material and permitting access of 45 the insulating liquid between the layers of paper.

3. An electric cable comprising a conductor insulated with laminated paper treated with wax having a melting point above 90° C. and the insulated conductor having an exterior coating of 50 paraffin wax having a melting point between room temperature and 90° C., a body of insulating fluid under pressure surrounding said conductor, and an enclosure for the fluid and conductor loosely surrounding the latter.
